United States Patent Office

Des. 210,455

Patented Mar. 12, 1968

210,455

TITRATION INSTRUMENT

Theodore Christie and Joseph J. Kregzdzys, Chicago, Ill.,
assignors to Precision Scientific Company, Chicago, Ill.,
a company of Illinois

Filed May 29, 1967, Ser. No. 7,286

Term of patent 3½ years

(Cl. D16—2)

FIG. 1

FIG. 2

FIGURE 1 is a perspective view of a titration instrument embodying the design of this invention, taken from the front right-hand corner of the instrument; and

FIG. 2 is a perspective view taken from the rear left-hand corner of the instrument of FIGURE 1.

We claim:

The ornamental design for a titration instrument, substantially as shown and described.
